UNITED STATES PATENT OFFICE.

GEORGE A. BOYDEN, OF BALTIMORE, MARYLAND, ASSIGNOR TO THE BOYDEN BRAKE COMPANY OF BALTIMORE CITY, OF SAME PLACE.

LOCOMOTIVE-DRIVER BRAKE.

SPECIFICATION forming part of Letters Patent No. 437,171, dated September 23, 1890.

Application filed July 25, 1890. Serial No. 359,940. (No model.)

To all whom it may concern:

Be it known that I, GEORGE A. BOYDEN, a citizen of the United States, residing at Baltimore, in the State of Maryland, have invented 5 certain new and useful Improvements in Locomotive-Driver Brakes, of which the following is a specification.

My invention relates to improvements in that class of driver-brakes which have one 10 brake-head bearing against each wheel and which are placed relatively on the same side of all the wheels; and my invention consists of such arrangement of levers in a vertical plane that the movement thereof will be in a 15 plane parallel to the movement of the brake-heads, thereby avoiding any loose connections, and to avoid any excessive strain on the levers, pins, and rods the brake-heads are suspended on levers in such manner that the 20 fulcrum thereof will exert its force against the heads, whereby double the power exerted from the floating levers will be applied to the brake-heads, as the floating levers are connected to the free ends of the suspension-levers, all of which I accomplish by the devices 25 hereinafter fully described and claimed, reference being had to the accompanying drawings, in which—

Figure 1 is a top view of one side of the 30 frame and wheel of a locomotive, showing the relative position of the brake parts thereto. Fig. 2 is a side view of the frame and wheels of a locomotive, showing the position of the shoes, rods, and brake-cylinder. Fig. 3 is a 35 top view showing the brake parts attached to a consolidation locomotive. Fig. 4 is a side view of Fig. 3. Fig. 5 is a detail side view showing the arrangement of the pull-rods, levers, beam, brake-head, and their attachment 40 to the frame. Fig. 6 is an end view of Fig. 5.

Similar numbers designate similar parts.

On each side of the locomotive are arranged fac-simile braking devices, which are secured together by suitable cross-beams to impart 45 rigidity and strength to the whole.

To the frame 7 of the locomotive is attached the brake-cylinder 8, provided with a piston and piston-rod 9, which transmit power to the brake mechanism through the link 10 and 50 right-angle crank 11, Fig. 4, or by the offset

lever 12, Fig. 2. The crank 11 or lever 12 is pivoted to the frame 7 by a suitable hanger 13. From the short arm of either is pivoted a pull-rod 14, provided with a suitable adjustable take-up device 15 to properly adjust the 55 parts as the shoes wear away.

Suspended from the frame 7 are the brake-heads 16, which are placed relatively on the same side of the several wheels 22, whereby when the braking force is applied the strain 60 will be in the same direction thereon.

To transmit power from the crank 11 or the lever 12 to the brake-heads 16, a series of pull-rods 14 are arranged with one end pivoted to or about the center of the floating levers 17, 65 with the other end pivoted to the top of the following floating lever, except the first one, which has one end attached to the adjusting device, and the last one, which has one end attached to the last cross-beam 18. The floating levers 17 are pivoted at the bottom to the suspension-levers 19 by means of the cross-beam 18, Fig. 6, which extend beyond the frame 7, and are attached to the brake device 70 on the opposite side in the same manner. 75

The suspension-levers 19 are attached to the frame 7 by suitable pins 20 and hangers 21. To the center of the suspension-levers 19 are fulcrumed the brake-heads 16, and so arranged that they will approach and recede 80 from the flange of the driver-wheels 22 in accordance with the vibration of the suspension-levers, and, as they move in the same plane with the floating levers, tight and substantial connections can be made between all the moving parts. As the brake-heads 16 are fulcrumed in the center of the suspension-levers 19, double the amount of pressure is exerted 85 on them over that which is applied to the bottom of the suspension-levers from the floating levers and pull-rods, thereby not requiring 90 so great a strain on these connections and parts to obtain the desired force on the brake-heads.

In Fig. 2, to balance the brake-heads, are 95 arranged the springs 23, which pass through the fulcrum-pins 24, with one end attached to the suspension-lever 19, and the other being against the bottom of the brake-heads.

The operation is as follows: When the 100

- pressure is admitted to the brake-cylinder 8, the piston-rod 9 transmits its force on the first pull-rod 14, which in time transmits the proper amount to the following pull-rod and 5 to its respective brake-head by means of the floating levers, and soon until the last brake-head is reached, on which all the remaining power is exerted, as there is no longer any need to transmit further.
- 10 The location where the central pivot-connections are made with the floating levers 17 and the pull-rods 14 depends on the required force to be exerted by that brake-head, and it is located to suit the weight carried by the 15 driver-wheel, or they can be located to equalize the pressure on all the driver-wheels.
- Having described my invention and the manner of operating, what I claim, and desire to secure by United States Letters Patent, is—
- 20 1. In a car or locomotive brake, the combination of two or more brake-heads arranged to bear against the wheels, the suspension-levers 19, that are free to vibrate in a vertical plane, the floating levers 17, pivoted to said suspension-lever and vibrating in the same 25 vertical plane therewith, and the pull-rods 14, for transmitting movement to said levers 19 and 17, for the purpose set forth.
2. In a car or locomotive brake, the combination of two or more brake-heads arranged to bear against the wheels, the suspension-levers 19, that are free to move in a vertical plane, the floating levers 17, pivoted to said suspension-levers and vibrating in same plane 30 therewith, the pull-rods 14, for transmitting movement to said levers 19 and 17, and the cross-beams 18, for the purpose set forth.
- 35

3. In a car or locomotive brake, the combination of two or more brake-heads placed relatively on the same side of each wheel, the 40 suspension-levers 19, that are free to vibrate in a vertical plane, the floating levers 17, pivoted to said suspension-levers and vibrating in the same plane therewith, the pull-rods 14, 45 for transmitting movement to said levers 19 and 17, and the cross-beams, for the purpose set forth.
4. In a car or locomotive brake, the combination of two or more brake-heads placed relatively on the same side of each wheel, the 50 suspension-levers 19, that are free to vibrate in a vertical plane, the floating levers 17, the lower ends of which are pivoted to the free 55 ends of said suspension-levers and thereby vibrate in the same plane therewith, the pull-rods 14, the ends whereof are connected, respectively, with the upper ends of said floating levers 17 and at a point in said levers 17 at or near the center thereof, whereby movement will be transmitted to the said suspension-levers 19, and whereby movement will be transmitted to the brake mechanism of the other drivers, and the cross-beams 18, whereby the brake mechanism on one side of the locomotive will be tied to that on the other side 60 thereof, for the purpose set forth.

In testimony whereof I affix my signature in presence of two witnesses.

GEORGE A. BOYDEN.
